UNITED STATES PATENT OFFICE.

JACOB HINKEL, OF OFFENBACH-ON-THE-MAIN, GERMANY, ASSIGNOR TO THE FIRM OF E. PH. HINKEL, OF OFFENBACH-ON-THE-MAIN, GERMANY.

RECEPTACLE FOR LIQUID OR SEMIQUID SUBSTANCES.

SPECIFICATION forming part of Letters Patent No. 718,625, dated January 20, 1903.

Application filed June 9, 1902. Serial No. 110,881. (No model.)

To all whom it may concern:

Be it known that I, JACOB HINKEL, a subject of the German Emperor, residing and having my post-office address at 56 Geleitsstrasse, Offenbach - on - the - Main, Germany, have invented certain new and useful Improvements in Receptacles for Liquid or Semiliquid Substances, of which the following is a specification.

10 The present invention relates to a bottle or receptacle for gum or mucilage which will allow of the removal of superfluous gum and at the same time prevent the smearing of the upper orifice or neck of the bottle and 15 the entrance of dust, also the gum coming out while not in use.

The novel feature of the invention essentially consists, in the fact, that inside the bottle near the neck cheeks or plates are 20 provided opposite each other and adapted to be pressed toward each other when the receptacle is in use by means of external press-buttons, but normally held apart by springs. When gum is to be taken from the recepta-

25 cle, the stick or brush, with gum thereon, is placed between the said cheeks and the latter are pushed toward each other, so that the superfluous gum on the stick or brush is caused to flow back into the receptacle.

30 A suitable form of construction, given as an example, is represented by the annexed drawing in elevation, partly in section.

At the neck of the otherwise ordinary bottle *a* and inside the latter two cheeks or 35 plates *b* are arranged opposite each other and provided with rods *c*, terminating in buttons or knobs, said rods extending to outside the bottle. The cheeks are held apart by

springs *d*. When the buttons or knobs on the rods *c* are pushed, the cheeks *b* are moved 40 toward each other, and when the stick or brush is then drawn between them they wipe it. The cheeks *b* are so formed that the gum left on them can easily flow off. When not in use, they lie tightly against the interior 45 sides of the bottle, so that should the latter pull over little or no gum can flow into the space between them and the mouth of the bottle. The rods are preferably screwed into the cheeks and can be easily unscrewed for the 50 purpose of removing and cleaning said cheeks.

It is obvious that various modifications can be made in this form of the device. For instance, one cheek only may be movable and the other fixed. What is essential is the 55 presence of two resilient and parallelly-guided cheeks moving in the interior of the receptacle and adapted to easily wipe gum downward. The device can of course also be used for other receptacles in which brushes are 60 used.

I claim—

A receptacle of the character described provided with two cheeks adapted to move in the interior of the receptacle, springs for 65 holding the cheeks separated, and means extending through the receptacle to move the cheeks toward each other, substantially as and for the purpose set forth.

In testimony whereof I have signed my 70 name to this specification in the presence of two subscribing witnesses.

JACOB HINKEL.
